REGULATING CARBURETOR

Calogero T. Corso, Bayville, N. Y.

Application March 21, 1956, Serial No. 572,989

2 Claims. (Cl. 261—56)

This invention relates to fuel and air mixing devices and the like, and particularly to a special regulating carburetor.

The main object of my invention is to provide a liquid fuel carburetor for supplying a fuel mixture to an internal combustion motor or engine in proper proportions to operate at peak efficiency.

Another important object of this invention is to provide a carburetor that is especially equipped to regulate the fuel and air mixture to nice proportions as desired.

A further object of the invention is to have such a carburetor which may be built-in upon the internal combustion engine with which it is connected to enhance the operation of both carburetor and engine due to their close association.

It is also a practical object of my invention to provide the carburetor with regulating means and special successive mixing chambers forming part of the carburetor structure.

Another quite practical object of the invention is to have a carburetor of the character indicated which is relatively simple to regulate and operate.

It is, of course, a definite object to have such a carburetor which is of sturdy and durable construction to fully provide the advantages of the invention due to its features in actual practice.

A most important object is to have a virtually self-adjusting and regulating carburetor balancing the air and fuel intake.

Other objects and advantages of my invention will appear in greater detail as the specification proceeds.

In order to facilitate ready comprehension of this invention for a proper appreciation of the salient features thereof, the invention is illustrated on the accompanying drawing forming part hereof, and in which:

Figure 1 is a side elevation, largely in section of a carburetor made according to the invention and embodying the same in a practical form;

Figure 2 is a section of the carburetor as taken on line 2—2 in Figure 1;

Figure 3 is another section of the carburetor as taken on line 3—3 in said Figure 1;

Figure 4 is a further section of the same carburetor as taken on line 4—4 in the same Figure 1;

Figure 5 is also a section of the carburetor as taken on line 5—5 in said Figure 1; and

Figure 6 is likewise a section of the same carburetor as taken on line 6—6 in aforesaid Figure 1, and

Figure 7 is a modification of the upper valve in Figure 1 also shown at the left in Figure 3.

Throughout the views, the same reference numerals indicate the same or like parts and features.

It is quite well accepted that an internal combustion engine or motor requires a relatively constant and ample supply of air and fuel mixture in order to function properly, and such supply depends on the operation of its carburetor. This carburetor should be capable of operating at high efficiency in great volume of mixture

2

delivered, and should certainly be capable of fine regulation. Also, it is essential that such a carburetor should be constant and reliable in operation so that the engine will operate uniformly well at all times and under perfect control. It is also important that the carburetor should be simple as possible in construction and not likely to get out of order, but instead be sturdy and durable.

As a result of considering this problem, I have succeeded in producing a regulating carburetor along the lines 10 already indicated which will now be described in detail in the following.

Hence, in the practice of my invention, and referring also to the drawing again, the carburetor, generally indicated at 7, primarily includes a cover casting or block 8 15 has a vertical air intake passage 9 and a horizontal air transfer passage 10 connected thereto controlled by a flap valve or damper type valve 11 with a control lever 12 rigid with the valve and capable of swinging it open or closed to varying degrees. At the extending end of this 20 block 8, passage 10 terminates in an upwardly directed chamber 13, closed above by a valve casting or plug 14 screwed into the upper interior thread 15 of chamber 13. This valve plug has a valve seat 16 for a valve 17 having a stem 18 guided vertically at 19 in casting 14, the latter 25 having a plurality of apertures 20, 20 above the valve seat 16 providing passage for air to passage 10 via chamber 13 from chamber 21 in plug or casting 14. Valve 17 is normally biased upwardly to its seat 16 by a spring 22 resting a cup 23 at the upper end of a regulating screw 30 24 having the head 25 by which to adjust it to increase or reduce resilient pressure of the spring against valve 17.

However, the main air supply enters the device from above passage 9, by way of an air-intake 26 in an upright tube member 27 secured upon casting 8 by screws 28, 28 35 and forming part of the upper casting 29. Through tube member 27 extends a transverse valve shaft 30 upon which is mounted a damper type valve 31 within passage 26, while exteriorly of tube 27 this shaft carries a lever 32 by which to operate valve 31 to control the tube passage 40 for incoming air. Upon lever 32 is fixed a crank-pin 33 extending through a hole 34 in a link 35 having an arcuate slot 36 at its other end in which a second crank-pin fits slidably at 37 which projects from the first mentioned lever 12, thus providing a mechanical connection between 45 both levers, as will be further explained.

In the mentioned casting 29 are bored passages 38, 39 at right angles to each other and at their outer ends plugged by screws 40 and 41 but interconnected at their angular junction, as evident in Figure 1, while in Figure 3 50 is shown a rearward branch passage 42 by which this passage arrangement connects with fuel injector tube 44 projecting into vertical air intake passage 26. Within casting 29 is also formed a cylindrical seat 43 occupied by a valve casing 45 having in turn an upwardly directed cylindrical valve chamber 46 with an internal thread 47 in the upper portion thereof. Into this valve chamber is screwed an upwardly threaded stationary valve member 48 having a valve chamber 49 with a lower tapering valve seat 50 for a vertically movable valve 51 having a valve 55 stem 52 extending slidably upward through a valve cap 53 screwed upon casing 48, a compression spring 54 biasing the valve downward into its seat. Although this so-called valve is so constructed that it may be lifted, its office is to determine the amount of liquid fuel flow 60 from a fuel tank 55 through injector 44 into air intake 26, the valve being a mere rotary adjusting member adjusted by turning the stem 52 by means of a handle or lever on this stem (not shown).

Casing 48 is provided with a peripheral channel or 70 passage 56 communicating with an upright central bore 57 in rotary regulating member 51 by a radial bore 58 which is one of three in the latter member capable of

registering more or less fully with the one aperture 59 in casing 48 (Figure 3). In addition, the belt channel 56 communicates through an outward passage 60 closed to the outside by a plug screw 61 but connecting inwardly with gas tank 55 by the channel 62. The central bore 57 in member 51 communicates at the bottom through bottom opening 63 in the member 45 and casting 29, interconnecting the injector 44 with tank 55.

The bottom casting 64 shown in Figures 1 and 4 is secured to the main casing 8 already described by screws 65, 65 etc., and has a downward central passage 66 forming a central chamber communicating at the top with air intake passage 26, this casting having an applied or integral bottom 67 forming a closure for the chambers in bottom casting 64. The latter has a partial circular partition or wall 68 with an opening 69 to a surrounding chamber 70 bounded by a second circular wall 71 having an opening 72 leading into a further chamber 73 likewise bounded by a circular wall 74 having an opening 75 leading into the general interior chamber 76 of the casting or block 64 as a whole. The chamber 76 therein has a passage 77 and 78 leading to the engine or motor for supplying the same with fuel and air mixture, which may be made rich, lean or average by adjustment of rotary regulating member 51 by turning its stem 52. Naturally, the engine produces a certain amount of suction which is communicated through openings 77 to the interior of the device and causes air to be drawn into air intake 26, this suction being governed by the amount of opening through passage 26 allowed by valve 31, and if this when open does not admit enough, its lever 32, being connected by link 35 to lever 12 of auxiliary air intake valve 11, the link will move far enough to present the far end of slot 36 to pin 37 and swing valve 11 open and also draw in air past spring loaded valve 17 through apertures 20, 20 in member 14. The engine suction thus largely governs the amount of air used and the fuel rate of flow set by regulating member 51 sets the pace for the engine to which openings 77, 78 communicate the fuel and air mixture that is developed by the air passing down through passages 26, 9 and 66 and through the alternately reversed circular chambers 70, 73 and 76, the air meanwhile passing fuel injector 44 in passage 26.

Instead of the valve casing 48 and valve or regulating member 51 being used for admitting and controlling the entry of fuel into the device, the valve structure shown in Figure 7 may be used, the casing 79 having the inner chamber 80 with the needle valve 81 cooperating with the aperture 82 in the bottom, while the spring 83 bears down on flange 84 of valve stem 85, and chamber 80 communicates with passage 60 in block 29 and through passage 62 with tank 55 when this valve assembly is in place. The spring 83 by its resilient pressure on valve 81 tends to regulate flow of fuel through valve aperture 86 and passages 60, 62, 63 and 82 and thus form an automatic regulating means for determining the amount of fuel fed to injector 44 from tank 55, which naturally determines the operation of the engine on an economical fuel saving basis. The air control is automatic between valves 11 and 31 due to their interconnection by levers 32 and 12 by link 35.

In any case, the described regulating carburetor serves to automatically regulate the amount of fuel and air that is fed to an engine to which it is connected when once set and connected to the engine and supplied with liquid fuel such as gasoline or the like. The alternate form of fuel valve casing 79 has the upper end threaded at 86 upon which a cap 87 is fitted through which valve stem 85 slidably extends like valve stem 52 through cap 53.

As already mentioned the present invention has the purpose of raising to a maximum degree the performance of the motor while keeping its consumption at a minimum.

Figure 3 of the drawings shows the gas regulation system with remote control. By eliminating the valve structure as shown in said Figure 3, including the members

48, 49, 51, 52 and 53, and replacing them by the structure as shown in Figure 7, a continuous gas regulation is obtained, while still retaining remote control at the driver's option.

- 5 The automatic air regulation is obtained by means of the structure shown in Figure 5 and at the left in Figure 1, of the drawing. The foregoing construction may be installed on all types of motors without including the semi-cylindrical baffles best shown in Figure 4 of the drawing.
10 It will be sufficient to regulate valve 17 by means of spring 22 pressed downwardly upon and held downwardly by means of the screw 25.

The system operates as follows: The air which enters from through intake member 26, whenever the motor operates at high speed is not sufficient to follow up without additional means the strong continuous suction of the motor. In order to relieve this condition, valve 17 starts to function and thus valve 11 with arm 12 and connecting rod 35 act on pin 34, and thereby on arm 32. Upon such action, butterfly valve 11 starts to open at the point at which the accelerator valve 31 has such an opening as to cause the development of approximately half speed operation of the motor.

Upon valve 11 starting to open, valve 17 opens only if suction prevails in chamber 13, i. e., if the motor operates without obtaining the air it requires, a suction is produced in said chamber 13 and only then does the valve 17 open and cause such amounts of air as the motor requires. Such air then passes through the air and gas mixing chamber 76 of casing 64 shown in transverse section in Figure 4.

Thus, the maximum performance of the motor is permanently obtained and regardless of the speed the motor will render highest performance at minimum consumption by eliminating all defects in carburation.

Having now fully described my invention, it is manifest that variations may be resorted to, and parts and features may be modified or used without others within the scope of the appended claims.

40 Hence, what I claim is:

1. In an adjustable internal combustion engine carburetor, the combination of a carburetor block having at one end a transverse air passage extending therethrough for connection to the intake of the engine and in an intermediate portion an open air intake passage leading downwards and connected within the block to the transverse passage, a fuel injector connected to a fuel supply tank extending to and projecting transversely into the downward air intake passage in one side thereof at a predetermined distance above said transverse passage, a first regulating means in said air intake passage for regulating the downward flow of air into the latter toward said transverse passage, a manually rotatably adjustable fuel valve disposed above the other end of said carburetor block in the connection between the fuel supply tank and the fuel injector and rotatable about a vertical axis, a valve casing rigid with the carburetor block at said other end thereof having a valve chamber and an auxiliary air intake passage extending upwards therefrom, said carburetor block above the level of the transverse passage having a further lateral passage interconnecting the valve chamber and the open air intake passage, a second regulating means in the further lateral passage, a link means interconnecting the first and second regulating means for simultaneous operation, a valve seat mounted in the auxiliary air intake passage in the valve casing, a vertically movable valve member below the valve seat for engaging with said valve seat in the valve chamber, a compression spring disposed beneath said valve member in said valve chamber biasing the valve member upward to said valve seat, and an adjusting screw extending from an exteriorly accessible position below said valve casing upwardly into the valve chamber and adjustably supporting said spring above the upper end of said adjusting screw.

2. In an adjustable carburetor according to claim 1, the features including having the carburetor block enlarged interiorly to form a lateral chamber at the lower end of the open air intake passage below the level of the fuel valve and of the vertically movable valve member, 5 said lateral chamber forming part of the transverse air passage in said block, and having a series of successively larger substantially concentric baffles surrounding the lower end of said open air passage with openings in alternately opposite sides of said baffles.
